CARPET.

No. 19,028.

Patented Apr. 9, 1889.

B

A

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 19,028, dated April 9, 1889.

Application filed March 7, 1889. Serial No. 302,835. Term of patent 3½ years.

To all whom it may concern:

Be it known that I, HENRY HUNT, a citizen of the United States, residing in Greenville, Hudson county, and State of New Jersey, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design is composed of a body, A, and border B. The body is composed of conventionalized leaf forms mostly scroll-shaped in character. These leaf forms overlap and in- 20 tertwine with each other. Groups of small gem-shaped flower forms are disposed between and upon the leaf forms. The border

B has a lower margin of uniform small ornamental figures. Above this is a wide band having long slender leaf forms deeply serrated and curved in long sweeping curves, and having small gem-shaped flower forms arranged in groups about and upon these leaf forms. Above this is an outer band or margin, the lower portion of which is ornamented 25 by small figures.

What I claim as new, and desire to secure by Letters Patent, is—

1. The design for a carpet, consisting of the body A, substantially as shown. 35
2. The design for a carpet, consisting of the border B, substantially as shown.
3. The design for a carpet, consisting of the body A and the border B, substantially as shown.

HENRY HUNT.
